(57) **CLAIM**

The ornamental design for a hot press module of a heating machine, as shown and described.

DESCRIPTION

FIG. 1 is a perspective view showing my new design for a hot press module of a heating machine;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof;
FIG. 8 is a perspective view showing from the rear view thereof;
FIG. 9 is a perspective view showing from the left view thereof;
FIG. 10 is a perspective view showing from the bottom view thereof;

FIG. 11 is a perspective view showing from the left side of the bottom view thereof; and,

FIG. 12 is a perspective view showing from the rear side of the bottom view thereof.

The broken lines seen in FIGS. 1 to 12 show portions of a hot press module of a heating machine that form no part of the claimed design.
